(57) **CLAIM**

The ornamental design for a headset computer with reversible display, as shown and described.

DESCRIPTION

FIG. 1 is a front perspective view of a headset computer with reversible display illustrating the Applicant's new design.

FIG. 2 is a front view of the headset computer of FIG. 1.

FIG. 3 is a top view of the headset computer of FIG. 1.

FIG. 4 is a left side view of the headset computer of FIG. 1.

FIG. 5 is a right side view of the headset computer of FIG. 1.

FIG. 6 is a rear view of the headset computer of FIG. 1.

FIG. 7 is a bottom view of the headset computer of FIG. 1.

FIG. 8 is a front perspective view of the headset computer of FIG. 1 with the boom and display positioned to be worn below a user's left eye; and,

FIG. 9 is a front perspective view of the headset computer of FIG. 1 in a storage position.

1 Claim, 9 Drawing Sheets
